UNITED STATES PATENT OFFICE

2,558,583

CLOTHES HANGER

Betty N. Robins, Detroit, Mich.

Application October 11, 1949, Serial No. 120,663

2 Claims. (Cl. 223—94)

1

This invention relates to coat hangers, and more particularly to a novel folding coat hanger which is capable of being collapsed into a comparatively small compass so that it may be easily transported or carried in a pocket of a garment, or even in a lady's handbag.

An object of the invention is the provision of a folding coat hanger wherein the shoulder portions are formed in sections and pivoted at a point adjacent a supporting hook, means being integrally made or connected to the sections of the shoulder portions so as to provide a positive support for clothes, such as a suit or coat, which is secured on the clothes hanger.

Yet another object of the invention resides in the provision of a foldable clothes hanger, the shoulder sections of which can be folded so as to fold into a comparatively small compass, yet while they are in their extended position, they are protected against collapsing by suitable means.

Still other objects reside in the provision of a folding clothes hanger that is strong, durable, efficient in operation, extremely simple in construction and manufacture, and which is comparatively inexpensive.

These, together with the various ancillary objects of the invention which will become apparent as the following description proceeds, are attained by this folding clothes hanger, a preferred embodiment of which has been illustrated in the accompanying drawings, by way of example only, wherein:

Figure 1 is a perspective view of the clothes hanger comprising the present invention, shown in its open and operative clothes supporting position;

Figure 2 is a perspective view of the clothes hanger shown in its folded position;

Figure 3 is a vertical sectional view as taken along line 3—3 in Figure 1, and being enlarged to show the structure in greater detail; and,

Figure 4 is a perspective view showing the means for retaining the folding coat hanger against collapse when it is in its operative position, in greater detail.

With continuing reference to the accompanying drawings wherein like reference numerals designate like parts throughout the various views, 10 generally represents the folding clothes hanger comprising the present invention. The clothes hanger 10 may be formed from any suitable material, such as paste-board, cardboard, thin sheet metal such as stainless steel, aluminum, or the like, or may be equally well made by

2

being pressed or moulded from any suitable plastic material, such as resins of thermo-setting characteristics.

The hanger 10 comprises a pin 12 which may optionally be a pivot or suitable screw. Journalled on the pin is a hook comprising a base section 14 having an aperture therethrough at one end, and a second section 16 having an aperture therethrough, in alignment with the aperture in the section 14. A screw 18 is provided for tightly, yet rotatably, securing the sections 14 and 16 together.

Journalled on the pin 12 are shoulder portions 20 and 22. These shoulder portions are provided with angularly extending lugs 24 and 26 which are angularly bent out of the plane of the portions 20 and 22 so as to engage each other to limit the rotational movement of the various portions. As seen from the view in Figure 1, the lugs 24 and 26 limit the counterclockwise movement of shoulder portion 20, while limiting the clockwise rotation of shoulder portion 22.

The shoulder portions 20 and 22 are also provided with angularly extending lugs 28 and 30 at their other ends. Rotatively connected, by means of a screw, pin, rivet, or the like 32 and 34, are a pair of extending members 36 and 38 which have angularly extending lugs 40 and 42 adjacent the ends which are pivoted to shoulder portions 20 and 22. As best shown in Figure 3, the lug 42 abuts against the lug 30 so as to prevent further clockwise rotation of the extending member 38. Likewise, lug 40 abuts against lug 28 to prevent the further counterclockwise motion of extending member 36.

The embodiment as shown in the drawings comprises a clothes hanger which is made from cardboard or paste-board, or other thin sheet material. It is made from this sheet material by being bent over on itself, as best seen in Figure 3, so as to suitably rigidify and strengthen the resulting structure.

The hanger is folded from the operating position as shown in Figure 1 to the closed position as shown in Figure 2, in the following manner. The extending members 36 and 38 are rotated upwardly, clockwise and counterclockwise respectively. When the members 36 and 38 lie flush with the shoulder portions 20 and 22, the shoulder portions together with the end portions are then rotated upwardly, clockwise for portion 20 and member 36, and counterclockwise for shoulder portion 22 and extending member 38. The hook portions 14 and 16 are then pressed inwardly together so as to provide the compact unit, shown

in Figure 2. Alternatively, the hook portions 14 and 16 may be provided with similar lugs as are the shoulder portions and extending members. However, it has been found that the friction setting of screw 18 is sufficient to satisfactorily maintain the hook about a rod on which the clothes hanger is to be placed, while the greater leverage upon the shoulder portions and extending members will overcome this frictional type securing means.

Since from the foregoing, the construction and advantages of this folding clothes hanger is readily apparent, further description is believed to be unnecessary.

However, since numerous modifications will readily occur to those skilled in this art after a consideration of the foregoing specification and the accompanying drawings, it is not intended to limit the invention to the precise embodiment of a clothes hanger shown and described, but all suitable modifications and equivalents may be resorted to which fall within the scope of the appended claims.

Having described the invention, what is claimed as new is:

1. A clothes hanger comprising a pin, a hook journalled on said pin, a pair of shoulder portions each journalled at one end thereof on said pin, each of said shoulder portions being provided adjacent each end thereof with a lug angularly disposed from the plane of said shoulder portions thereby limiting rotation of said shoulder portions in one direction, a pin secured in the other end of said shoulder portions, a lug on said other end of each of said shoulder portions, a pair of extending members journalled at a first end on the pins secured in said other end of said shoulder portions, each of said extending members being provided at said first end with a

lug angularly disposed from the plane of said extending members for engagement with the lugs on said other end of said shoulder portions thereby limiting the rotation of said extending members relative to said shoulder portions in one direction.

2. A clothes hanger comprising a pin, a hook journalled on said pin, said hook being formed in sections, means rotatably securing said sections to each other, a pair of shoulder portions each journalled at one end thereof on said pin, each of said shoulder portions being provided adjacent each end thereof with a lug angularly disposed from the plane of said shoulder portions thereby limiting rotation of said shoulder portions in one direction, a pin secured in the other end of said shoulder portions, a lug on said other end of each of said shoulder portions, a pair of extending members journalled at a first end on the pins secured in said other end of said shoulder portions, each of said extending members being provided at said first end with a lug angularly disposed from the plane of said extending members for engagement with the lugs on said other end of said shoulder portions thereby limiting the rotation of said extending members relative to said shoulder portions in one direction.
